drawing(s)/photograph(s) will be provided by the Office upon request and payment of the necessary fee.

FIG. 1 is a perspective view of an injection molding machine, showing our new design;

FIG. 2 is an enlarged partial view thereof;

FIG. 3 is an enlarged partial view thereof;

FIG. 4 is an enlarged partial view thereof;

FIG. 5 is an enlarged partial view thereof;

FIG. 6 is an enlarged partial view thereof;

FIG. 7 is an enlarged partial view thereof;

FIG. 8 is an enlarged partial view thereof;

FIG. 9 is an enlarged partial view thereof;

FIG. 10 is an enlarged partial view thereof;

FIG. 11 is an enlarged partial view thereof;

FIG. 12 is a perspective view of the injection molding machine in another embodiment;

FIG. 13 is an enlarged partial view thereof;

FIG. 14 is an enlarged partial view thereof;

FIG. 15 is an enlarged partial view thereof;

FIG. 16 is an enlarged partial view thereof;

FIG. 17 is an enlarged partial view thereof;

FIG. 18 is an enlarged partial view thereof;

FIG. 19 is an enlarged partial view thereof;

FIG. 20 is an enlarged partial view thereof;

FIG. 21 is an enlarged partial view thereof;

FIG. 22 is an enlarged partial view thereof;

FIG. 23 is an enlarged partial view thereof;

FIG. 24 is an enlarged partial view thereof; and,

FIG. 25 is another view of the image of FIG. 19.

Portions shown in broken lines form no part of the claimed design.

Graphic elements within the broken line bounded portions of FIG. 26 form no part of the claimed design.
